(57) **CLAIM**

The ornamental design for a smart curtain opener, as shown and described.

DESCRIPTION

FIG. 1 is a perspective view of a smart curtain opener showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of the smart curtain opener shown within the area designated as 9 in FIG. 2.

The broken lines in the drawings are for the purpose of illustrating portions of the smart curtain opener that form no part of the claimed design. The dot-dashed broken line in FIGS. 2 and 9 shows the boundary of the enlarged view and forms no part of the claimed design.
